UNITED STATES PATENT OFFICE

ANDREW THOMA, OF CAMBRIDGE, MASSACHUSETTS, ASSIGNOR TO NORTH AMERICAN CHEMICAL COMPANY, OF CAMBRIDGE, MASSACHUSETTS, A CORPORATION OF MASSACHUSETTS

METHOD OF FILLING SHOES

Application filed February 20, 1931. Serial No. 517,236.

This invention consists in a new method or process of filling the bottom cavities of shoes. In its more complete exemplification, and particularly when applied to welt shoes, the process includes also the flattening and compressing of the welt seam and the leveling of the welt itself, along with the spreading and pressing of the shoe filler within the cavity.

In laying and spreading plastic shoe bottom filler in the bottom cavities of shoes it has heretofore been the practice, in the case of bulk filler, to dip or scoop a quantity of filler, suitable for a single shoe cavity, by means of a hot spreading knife or spatula out of a larger mass or bulk of filler, usually previously softened and conditioned for spreading. The operator would then deposit the segregated quantity of filler in the shoe bottom cavity and spread it within the cavity by means of the spatula in much the same manner as a mason lays and spreads mortar with a trowel. Usually the filler layer was also finally smoothed by passing a roller back and forth over its surface. In laying or spreading individual, leaf-like pieces of plastic filler material, which have recently come on the market, the operator would place a filler piece in the shoe bottom cavity and then in spreading the same follow a similar procedure to that used in spreading bulk filler, namely, to spread the pre-conditioned filler piece throughout the cavity by means of a hot spatula and/or by passing a roller back and forth over the filler surface.

With the method of spreading and pressing the filler according to the present invention, powerful pressure is applied by the surface of a press substantially flatwise of the shoe cavity, and at substantially one and the same time over the whole area of the cavity, the filler and the rest of the shoe bottom under treatment, and in a direction substantially normal or perpendicular to the shoe bottom. Simultaneously with said spreading and pressing operation, the filler layer, and indeed the entire surface of the shoe bottom, may be subjected to a vibratory motion of the press surface, preferably a twisting or back and forth motion of partial rotation in a plane transverse to the direction of

pressure and substantially coincident with the plane of the work. Such vibratory or back and forth movement of the press upon the filler and shoe bottom during the spreading and pressing operation facilitates the proper spreading and distribution of the filler throughout the cavity and into all its irregularities and crevices, aids in compacting and condensing the filler layer, and, in the case of a welt shoe, aids in flattening, compressing and condensing the welt seam, and leveling or evening it down to the plane of the filler and the welt itself. During the same pressing operation the welt is also leveled or evened up and set in the plane of the rest of the shoe bottom.

The plastic filler used in my new method, whether in bulk form or piece form, is preferably of the kind which requires softening or conditioning for spreading, as by heat, and therefore the application of heat to the filler during the spreading and pressing operation is included in the invention. The filler may also be of the kind whose composition requires heat to effect a chemical or physical reaction at the time of laying. For example, it may contain starch paste; when such filler is spread under the influence of heat, the heat takes out water and sets the paste. Or, it may be a filler in which the binder is present in dispersed condition; when such filler is spread under the influence of heat, the heat evaporates the dispersing agent and starts the coagulation of the binder. Other known types of filler are beneficially spread in the presence of heat. Although there are important advantages in using a heat-plastic or heat-responsive filler and in applying heat at the very time of and during the spreading and pressing of the filler, the invention in its broader aspects is not limited to this particular feature but is intended broadly to cover the method even though the filler is pre-heated or pre-conditioned before being placed in the machine, or is of a kind which can be spread cold without pre-conditioning.

The practice of the process is not dependent on the use of any particular machine, but may be carried out by various forms of ma-

chine. A machine well adapted for the purpose is described in the application of Alfred H. Avery for patent Serial No. 517,237, filed February 20, 1931, and I will therefore use 5 that machine for the purpose of illustration without, however, intending in any way to limit my process to that or any other particular machine.

Other machines suitable for performing 10 certain of the functions of the invention are illustrated in application of Alfred H. Avery for patent Serial No. 481,129, filed September 11, 1930 and Serial No. 516,862, filed February 19, 1931.

15 In the accompanying drawings, only such parts of the machine of said application Serial No. 517,237 are shown and described as are necessary to an understanding of the method constituting the subject matter of 20 the present application.

Fig. 1 is a side view of the machine showing the press in operative position closed upon a shoe;

25 Fig. 2 is a side view, partly in section, showing the press in open or inoperative position with a shoe in position before being operated upon;

30 Fig. 3 is a cross section through the forepart of a shoe, on its last, with the welt attached ready to receive the filler;

35 Fig. 4 is a similar cross section showing an unspread quantity of filler deposited in the shoe bottom cavity, and the welt resting on the welt support;

Fig. 5 is a similar cross section showing 40 the result at the completion of the spreading and pressing operation.

For convenience, the same reference numerals will be used as for corresponding 45 parts in said applications Serial No. 517,237 and Serial No. 516,862.

Mounted on the front of the machine frame is a pressing and spreading pad, indicated generally at 20, which has a smooth, 50 generally flat press surface 58 on its under side. The pad 20 is preferably constructed as described in detail in said applications Serial No. 517,237 and Serial No. 516,862 to provide a hot, flexible and slightly yielding press surface, which is normally slightly bowed or convex.

Below the pad 20 is a swinging frame 76, journaled on the machine frame at 77. The swinging frame carries the shoe supports 55 consisting of a toe rest 101, and a pair of welt supporting plates 45. When the swinging frame 76 is swung upwardly, by mechanism described in said application Serial No. 517,237, with a shoe S carrying a quantity of 60 unspread filler in its bottom cavity mounted in position on the shoe supports, the filler and the entire shoe bottom are forcibly pressed against the hot press surface of pad 20, whose area is sufficiently extensive to cover the 65 tire area of the shoe bottom to be operated

upon. The pressure exerted by the press surface of pad 20 is thus applied substantially flatwise of the shoe bottom at substantially the same time over the whole area of the work and in a direction substantially 70 normal or perpendicular to the shoe bottom, with the result that not only is the filler spread and distributed throughout the cavity, and simultaneously heated if a heat-plastic filler is used, but the peripheral walls 75 of the cavity (the welt seam) are crushed down, flattened and pressed along with the filler layer, and the welt W is pressed and set in its leveled position.

The pad 20 is fixed to the lower end of a 80 stem or spindle 68 journaled on a vertical axis on the machine frame. Fixed to the upper end of the stem 68 is a laterally extending crank arm 70, which is connected by a pitman 71 to an eccentric 72 fast on shaft 73. When the machine is in operation this mechanism oscillates or vibrates pad 20 on its vertical axis, thereby imparting to the working face or press surface of the pad a 85 vibration or back and forth movement of partial rotation in a plane transverse to the direction of pressure and substantially coincident with the plane of the shoe bottom surface, during the spreading and pressing operation.

90 For a more complete and detailed description of the machine used for illustrating the process, reference is made to said applications Serial No. 517,237 and Serial No. 516,862. But as the present invention consists in 95 the process or method and not in the machine, and as the method may be performed by other machines, the foregoing description will sufficiently explain the action of the principal mechanical factors recommended for practicing the method.

100 In carrying out the method on a welt shoe the operator deposits in the shoe bottom cavity, which is defined by the welt seam W' around the forepart of the shoe, a quantity of 105 spreadable filler suitable when spread for filling the cavity. The filler used may be either in bulk form or in piece form. In either case the unit of filler deposited in the cavity will differ in shape from the shape of the cavity, being somewhat thicker than the depth of the cavity and smaller than the area of the cavity. In Figs. 2 and 4 a lump of bulk filler is shown at F.

110 The operator then shoves the shoe S, still 115 on its last L and carrying the unspread filler F in its bottom cavity, toe foremost into the machine with its forepart resting on the toe rest 101 and its welt resting on the welt supporting plates 45, 45.

120 A welt, when first attached to a shoe, is 125 usually not flat and level with the shoe bottom but somewhat uneven and inclined toward the upper as illustrated at W in Fig. 3. When the shoe is placed in position with the

welt resting on the welt supports 45, 45, the welt is straightened and leveled up into its proper plane.

Upon the engagement of the toe of the 5 shoe with the trip 104, the shoe supports are swung upward toward the spreading and pressing pad 20 by mechanism more fully described in my said application Serial No. 517,237. The filler F is thereby forced under 10 powerful pressure into spreading and pressing engagement with the hot surface of pad 20. The pressure is applied by the hot press surface substantially flatwise of the shoe bottom at substantially the same time over the 15 whole area of the cavity, the filler, the welt seam and the welt, and in a direction substantially perpendicular or normal to the shoe bottom. Simultaneously with the pressing and spreading operation the press surface is given a vibratory or back and forth motion of partial rotation, as by the mechanism more fully described in the said application Serial No. 517,237, which facilitates the complete spreading and distribution of 20 the filler within the cavity and the compacting of the ultimate filler layer under the direct pressure. At the same time the press surface of the hot pad 20, which extends over the whole area of the shoe bottom, crushes down, flattens and compresses the welt seam, 25 and presses and sets the welt itself in its proper flat position, level with the rest of the shoe bottom.

In filling McKay shoes, or other shoes 30 which have no welt, substantially the same method is followed, excepting that the welt supports are not used and the flatwise pressure does not flatten a welt, but does press the inturned margin of the upper, which 35 defines the shoe bottom cavity of a McKay shoe, along with the filler layer.

The flexible surface of pad 20 conforms to the shape of the shoe bottom and when it engages the welt seam in a welt shoe or the 40 inturned margin of the upper in a McKay shoe, it forms a barrier which prevents overflow of the filler beyond the walls of the cavity and confines the spreading of the filler within the cavity. Any excess or surplus 45 filler will be extruded rearwardly toward the shank of the shoe and may be readily scraped or knocked off.

In the filling of shoes by hand, as heretofore practiced, there was no substantial or 50 effective variation in the pressure applied to different shoes; and as that pressure was applied merely by the hand of the operator it was a comparatively light pressure and amounted to little more than a hand smoothing operation. The best shoemaking calls 55 for more powerful pressure and for different degrees of pressure for different types of shoes. The present method not only provides the requisite degree of pressure properly to spread, compact and condense the 60 filler layer, but also provides for applying

different degrees of pressure to different shoes, since the ultimate or maximum pressure exerted between the presser pad 20 and the shoe bottom depends on the spring 84, whose tension may be adjusted as described 70 in said application Serial No. 517,237. Thus the present method comprises further a single pressure, of the kind already described, which progressively increases up to the desired predetermined maximum suitable for 75 the particular work in hand.

Again, in filling welt shoes by the old hand method it was difficult if not impossible to force the wax tailings, or other waterproof binder used in the filler to flow into and 80 through the stitch holes and stitches which extend through the welt seam uniting the welt, upper and lip. With the present method the forcible lateral spreading of the filler under powerful pressure, aided by heat which 85 liquefies or softens the binder, drives the binder into the stitch holes and stitches of the welt seam and so greatly improves the waterproof qualities of the shoe.

I claim:

1. The method of filling shoes which comprises depositing in the bottom cavity of a shoe a quantity of spreadable shoe filler, suitable when spread for filling the cavity but differing in shape from the shape of the cavity, and spreading the filler laterally to the confines of the cavity and compressing the same by powerful pressure applied substantially flatwise by a press acting directly 95 on the filler and at substantially the same 100 time over the whole area of the cavity and in a direction substantially normal to the shoe bottom.

2. The method of filling shoes which comprises depositing in the bottom cavity of a 105 shoe a quantity of spreadable shoe filler, suitable when spread for filling the cavity but differing in shape from the shape of the cavity, spreading the filler laterally to the 110 confines of the cavity and compressing the same by powerful pressure applied substantially flatwise by a press surface at substantially the same time over the whole area of the cavity and in a direction substantially normal to the shoe bottom, and simultaneously subjecting the work to a vibratory motion of the press surface in a plane transverse to the direction of pressure.

3. The method of filling shoes which comprises depositing in the bottom cavity of a 120 shoe a quantity of spreadable shoe filler, suitable when spread for filling the cavity but differing in shape from the shape of the cavity, spreading the filler laterally to the 125 confines of the cavity and compressing the same by powerful pressure applied substantially flatwise by a press surface at substantially the same time over the whole area of the cavity and in a direction substantially normal to the shoe bottom, and simultane-

ously subjecting the work to a vibratory motion of partial rotation of the press surface in a plane transverse to the direction of pressure.

5. 4. The method of filling shoes which comprises depositing in the bottom cavity of a shoe a quantity of spreadable shoe filler, suitable when spread for filling the cavity but differing in shape from the shape of the cavity, spreading the filler laterally to the confines of the cavity and compressing the same by powerful pressure applied substantially flatwise by a press acting directly on the filler and at substantially the same time over the whole area of the cavity and in a direction substantially normal to the shoe bottom, and applying heat to filler during the spreading and pressing operation.

5. The method of filling shoes which comprises depositing in the bottom cavity of a shoe a quantity of spreadable shoe filler, suitable when spread for filling the cavity but differing in shape from the shape of the cavity, spreading the filler laterally to the confines of the cavity and compressing the same by powerful pressure applied substantially flatwise by a press surface at substantially the same time over the whole area of the cavity and in a direction substantially normal to the shoe bottom, and simultaneously subjecting the work to a vibratory motion of the press surface in a plane transverse to the direction of pressure, and applying heat to the filler during the spreading and pressing operation.

6. The method of filling welt shoes which comprises depositing in the bottom cavity defined by the welt seam a quantity of spreadable shoe filler, suitable when spread for filling the cavity but differing in shape from the shape of the cavity, spreading the filler laterally to the confines of the cavity and compressing the same by powerful pressure applied substantially flatwise of the cavity by a press acting directly on the filler and in a direction substantially normal to the shoe bottom, and at the same time flattening the welt seam by pressure.

7. The method of filling welt shoes which comprises depositing in the bottom cavity defined by the welt seam a quantity of spreadable shoe filler, suitable when spread for filling the cavity but differing in shape from the shape of the cavity, spreading the filler laterally to the confines of the cavity and compressing the same by powerful pressure applied substantially flatwise of the cavity by a press acting directly on the filler and in a direction substantially normal to the shoe bottom, and at the same time flattening the welt seam by pressure and leveling the welt.

8. The method of filling welt shoes which comprises depositing in the bottom cavity defined by the welt seam a quantity of spreadable shoe filler, suitable when spread for

filling the cavity but differing in shape from the shape of the cavity, spreading the filler laterally to the confines of the cavity and compressing the same by powerful pressure applied substantially flatwise of the cavity by a press surface in a direction substantially normal to the shot bottom, and at the same time flattening the welt seam by pressure and simultaneously subjecting both the filler and the welt seam to a vibratory motion of the press surface in a plane transverse to the direction of pressure.

9. The method of filling welt shoes which comprises depositing in the bottom cavity defined by the welt seam a quantity of spreadable shoe filler, suitable when spread for filling the cavity but differing in shape from the shape of the cavity, spreading the filler laterally to the confines of the cavity and compressing the same by powerful pressure applied substantially flatwise of the cavity by a press surface in a direction substantially normal to the shoe bottom, and at the same time flattening the welt seam by pressure and simultaneously subjecting both the filler and the welt seam to a vibratory motion of partial rotation of the press surface in a plane transverse to the direction of pressure.

10. The method of filling welt shoes which comprises depositing in the bottom cavity defined by the welt seam a quantity of spreadable shoe filler, suitable when spread for filling the cavity but differing in shape from the shape of the cavity, spreading the filler laterally to the confines of the cavity and compressing the same by powerful pressure applied substantially flatwise of the cavity by a press surface in a direction substantially normal to the shoe bottom and at the same time flattening the welt seam by pressure, and simultaneously subjecting both the filler and the welt seam to a vibratory motion of the press surface in a plane transverse to the direction of pressure and applying heat to the filler and welt seam during the spreading and pressing operation.

11. The method of filling welt shoes which comprises depositing in the bottom cavity defined by the welt seam a quantity of spreadable shoe filler, suitable when spread for filling the cavity but differing in shape from the shape of the cavity, spreading the filler laterally to the confines of the cavity and compressing the same by powerful pressure applied substantially flatwise of the cavity by a press acting directly on the filler and in a direction substantially normal to the shoe bottom, and at the same time flattening the welt seam by pressure, and applying heat to the filler and welt seam during the spreading and pressing operation.

12. The method of filling shoes which comprises depositing in the bottom cavity of a shoe a quantity of spreadable shoe filler, suitable when spread for filling the cavity

but differing in shape from the shape of the cavity, spreading the filler laterally to the confines of the cavity and compressing the same by powerful pressure applied substantially flatwise by a press acting directly on the filler and at substantially the same time over the whole area of the cavity and in a direction substantially normal to the shoe bottom, and preventing overflow of the filler beyond the walls of the cavity during said spreading and pressing operation.

13. The method of filling shoes which comprises depositing in the bottom cavity of a shoe a quantity of spreadable shoe filler, suitable when spread for filling the cavity but differing in shape from the shape of the cavity, spreading the filler laterally to the confines of the cavity and compressing the same by powerful pressure applied substantially flatwise by a press acting directly on the filler and at substantially the same time over the whole area of the shoe bottom and in a direction substantially normal to the shoe bottom, and engaging the press surface with the top of the walls of the cavity to prevent overflow of the filler beyond the walls of the cavity during said spreading and pressing operation.

14. The method of filling shoes which comprises depositing in the bottom cavity of a shoe a quantity of spreadable shoe filler, suitable when spread for filling the cavity but differing in shape from the shape of the cavity, and spreading the filler laterally to the confines of the cavity and compressing the same by a single stroke of pressure applied by a press acting directly on the filler and substantially flatwise and of progressively increasing power up to a predetermined maximum.

15. The method of filling a welt shoe which comprises depositing in the bottom cavity of the shoe a quantity of spreadable shoe filler containing a binder capable of flowing under pressure, spreading the filler laterally to the confines of the cavity and compressing the same by pressure applied by a press acting directly on the filler and substantially flatwise, and simultaneously forcing the binder to flow under the pressure from the cavity into the stitch holes of the welt seam.

16. The method of filling a welt shoe which comprises depositing in the bottom cavity of the shoe a quantity of spreadable shoe filler containing a binder capable of flowing under pressure, spreading the filler laterally to the confines of the cavity and compressing the same by pressure applied by a press acting directly on the filler and substantially flatwise, and simultaneously applying heat to the filler to render the binder more fluid and forcing the fluid binder to flow under the pressure from the cavity into the stitch holes of the welt seam.

17. The method of filling shoes which comprises depositing in the bottom cavity of a shoe a quantity of spreadable shoe filler, suitable when spread for filling the cavity but differing in shape from the shape of the cavity, and causing it to flow laterally in all directions to the confines of the cavity by subjecting it to substantially flatwise pressure applied over the whole area of the cavity at substantially the same time and in a direction substantially normal to the shoe bottom, simultaneously subjecting the filler to heat, and engaging the press surface with the top of the walls of the cavity to prevent overflow of the filler beyond the walls of the cavity during the pressing operation.

Signed by me at Boston, Massachusetts, this 18th day of February, 1931.

ANDREW THOMA.
